his attorney.

UNITED STATES PATENT OFFICE

FRANK E. GREEN, OF PITTSBURGH, PENNSYLVANIA

FEED CHUCK

Application filed February 18, 1930. Serial No. 429,345.

In certain classes of machinery, such for instance as single or multiple spindle automatic screw machines, a feed chuck is employed for intermittently feeding forwardly 5 the stock, and my invention relates to such feed chucks.

A common form of such chuck is a tubular piece or spring or tool steel having its wall slit longitudinally and inbent toward the 10 axis of the tube to form gripping portions or fingers. Such feed chucks are inefficient in operation and short lived, as the fingers become worn and present sharp edges to the stock, thus marring the latter, and the gripping 15 action of the spring metal is impaired and thus the stock is not fed uniformly. When either of these contingencies occur the entire chuck, made of expensive material, must be scrapped, or first annealed, then machined and then rehardened, often with poor 20 results.

Again in the case of feed chucks of the character above described there are no means for adjusting or regulating the action of the 25 gripping fingers, as for instance to compensate for wear or loss of tension.

In my improved feed chuck the grippers are separate elements which are removably and interchangeably mounted in a tubular holder, so that should the grippers become worn or lose their tension they can be quickly and conveniently removed from the holder and others substituted in their place. Thus 30 the loss of the entire chuck is avoided.

Again my improved feed chuck is provided with means for regulating and adjusting the gripping action of the fingers so as to obtain the most efficient and uniform feed for a given character or cross-section of stock or to compensate for finger wear or loss of tension. 35

Where different diameters or cross section of stock are to be worked, suitable grippers are installed in the holder.

Other novel features of construction, and of arrangement of parts, will appear from the following description.

In the accompanying drawings, wherein I have illustrated a practical embodiment of 50 the principles of my invention, Fig. 1 is an

elevation of the feed chuck with a length of round stock held therein.

Fig. 2 is an enlarged longitudinal section of the feed chuck.

Figs. 3 and 4 are sectional views taken along the lines 3—3 and 4—4, respectively, in Fig. 2, illustrating the gripping of round stock.

Figs. 5 and 6 are views similar to Figs. 3 and 4, respectively, but showing the chuck 60 arranged to grip square stock.

Figs. 7 and 8 are views similar to Figs. 3 and 4, respectively, but showing the chuck arranged to grip hexagonal stock.

Fig. 9 is a view similar to Fig. 3 but showing two grippers instead of three.

Fig. 10 is a perspective of one of the grippers shown in Figs. 2, 3 and 4.

Fig. 11 is a broken perspective of one of the grippers shown in Figs. 5 and 6.

Referring first to Figs. 1, 2 and 3 of the drawings, 1 represents the tubular holder of the chuck. The holder is a steel tube, such as a piece of seamless tubing. The rear end of the holder is interiorly threaded as at 2 so that the nipple 3 may be screwed into the same. The other end of the nipple is screwed into the feed tube 4 of the screw machine. The nipple 3 is provided with a central annular shoulder 5 which may serve to limit the insertion of the nipple into an associated element or for the application of a wrench or other tool for turning the nipple.

The front end of the nipple 3 which is inserted into the holder 1 has its annular edge bevelled to form an annular wedging shoulder 6. The front end of the tubular holder 1 is provided with an annular internal wedging shoulder 7 which may, if desired, be formed by inwardly upsetting the end of the holder. The shoulders 6 and 7 are opposed to each other and may be caused to approach or diverge by screwing in or unscrewing the nipple relative to the holder.

The grippers are formed of strips of 95 spring steel material first cut and pressed into shape and then tempered. The end portions 8 of the strips are of arcuate cross-sectional shape and together fit the bore of the holder 1 adjacent to its ends while the 100

intermediate portions are narrowed and pressed inwardly to form the spring fingers 9 which bear against and grasp the stock. Where the stock is round, the fingers are 5 arcuate to fit the stock.

In Figs. 2, 3 and 4, three grippers are shown employed to grasp the round stock 10 while in Fig. 9 but two grippers are employed.

10 One of the grippers employed in Figs. 2, 3 and 4 is illustrated in Fig. 10.

Where stock of square cross-sectional shape is to be gripped by the chuck, as shown at 10^a in Figs. 5 and 6, I prefer to use the form 15 of grippers illustrated at 8^a in Fig. 11, four of the same being employed, the end portions of the grippers being arcuate to fit together in the bore of the holder while the intermediate or finger portions of the grippers are flat to bear against the four sides of the square stock 10^a.

20 Where hexagonal stock, such as shown at 10^b in Figs. 7 and 8, is to be gripped by the chuck I prefer to employ three grippers 25 8^b—9^b, with their flat fingers gripping alternate sides of the stock.

25 The ends of the grippers are beveled as at 11 to mate with the wedging shoulders 6 and 7 so that by screwing in the nipple 3 relative 30 to the holder 1, the grippers will be compressed longitudinally and thus the fingers will be forced inwardly toward the axis of the holder. Thus by adjusting the nipple relative to the holder the grip of the fingers 35 on a predetermined diameter or shape of stock may be regulated so that the feed will be proper and uniform.

40 In like manner any wear or loss of resiliency or gripping power in the fingers may be taken up or compensated for.

45 The stock is easily inserted through the chuck without danger of breakage of machine parts.

When it is desired to remove or replace 45 the grippers, the nipple is unscrewed from the end of the holder, the grippers pulled out and new ones substituted, and the nipple screwed into place.

50 It is obvious that when the chuck is to be changed to suit different stock or becomes inefficient from use or other causes, the only replacement is that of the grippers, instead of the whole chuck as is now necessary.

55 My improved chuck is of inexpensive construction but strong and durable.

One striking advantage of my invention arises from the fact that finished or polished stock may be fed with it without danger of the stock becoming scratched or marred.

60 Again the end of the stock slips easily into the chuck and therefore it is not necessary to grind or bevel the end of the stock preparatory to placing it in the machine. Likewise when but a short stub of the stock is left and

65 the same is pulled out of the chuck as the latter is retreated, when the chuck is advanced the end of the stub will easily reenter the stub without danger of breakage.

70 What I desire to claim is:—

1. In a feed chuck, the combination of a tubular holder, a plurality of spring metal grippers having end portions to fit the holder and removably mounted in said holder, said grippers having intermediate portions bowed inwardly toward the axis of the holder to 75 form stock-gripping fingers, and means for compressing the grippers longitudinally to increase their stock-gripping action.

2. In a feed chuck, the combination of a tubular holder, a plurality of spring metal grippers mounted within the holder and having end portions to fit the holder, said grippers having portions bowed inwardly toward the axis of the holder to form stock-gripping fingers and a wedging abutment positioned 80 adjacent to each end of the holder and engaging the ends of the grippers.

3. In a feed chuck, the combination of a tubular holder, a plurality of spring metal grippers mounted within the holder and having end portions to fit the holder, said grippers having portions pressed inwardly toward the axis of the holder to form stock-gripping fingers, a wedging abutment positioned 85 adjacent to each end of the holder and engaging the ends of the grippers, and means for varying the distance between the abutments whereby to regulate the action of the fingers.

4. In a feed chuck, the combination of a tubular holder, an internal wedging shoulder at the one end of the holder, a member inserted into the other end of the holder and forming a second internal shoulder, a plurality of 100 spring steel grippers having end portions to fit the holder mounted in said holder between said shoulders, the intermediate portions of the grippers being bowed inwardly to form stock-gripping fingers.

5. In a feed chuck, the combination of a tubular holder having an internal wedging shoulder at one end, a member screwed into the other end of the holder and forming a second internal wedging shoulder, and a plurality of 110 spring metal grippers having end portions to fit the holder held in said holder between said shoulders, the intermediate portions of said grippers being bowed inwardly to 115 form stock-gripping fingers, and the compression of said fingers being regulated by the degree of insertion of said member in said holder.

120 Signed at Pittsburgh, Pa., this 25th day of January, 1930.

FRANK E. GREEN.
